BY *Petherston Haugh & Co*
ATTY'S

UNITED STATES PATENT OFFICE.

GEORGE HAGAR GILCHRIST, OF OTTAWA, ONTARIO, CANADA.

DRAWING BOARD.

1,380,646.

Specification of Letters Patent. Patented June 7, 1921.

Application filed October 20, 1919. Serial No. 331,894.

To all whom it may concern:

Be it known that I, GEORGE HAGAR GILCHRIST, a subject of the King of Great Britain, a resident of the city of Ottawa, Province of Ontario, Dominion of Canada, have invented certain new and useful Improvements in Drawing-Boards, of which the following is a specification.

This invention relates to improvements in drawing boards, and the objects of the invention are to permit of the drawing board being rotated through any desired angle in a horizontal plane, to provide means for a visual indication of the angular displacement of the board, to permit of a T-square ruler or other drawing instrument, being slidably adjusted so that parallel lines can be readily drawn to permit of the instrument and the guides, supporting the said instrument, being graduated, so that lines of predetermined length can be drawn and spaced apart as desired.

With the above and other objects in view, the invention consists essentially of the improved construction particularly described and set forth in the following specification and accompanying drawings forming part of the same.

In the drawings:

Figure 1 is a perspective view of the improved drawing table.

Fig. 2 is a longitudinal section of the same.

Like characters of reference refer to like parts in the several figures.

Referring to the drawings, A represents a table comprising a top 10 supported by legs 11, the top being provided with lateral guide members 12 which may be graduated on the upper face.

The top 10 is provided at a central point with a bearing 13 designed to rotatably engage with the stub spindle or pin 14 carried by the pulley 15 which is rigidly attached to the board 16, so that the board and pulley are designed to be simultaneously rotated in a horizontal plane on the stub spindle or pin 14, as a pivot.

To eliminate friction between the pulley 15 and the top 10 of the table, I provide a plurality of rollers 17 designed to engage with the race 18, and in this way vibration of the board and pulley during rotation is eliminated and the turning of the table can be very readily accomplished.

At one side of the table 10 a pulley 19 is rotatably mounted, and a strap 20 of a

material, which does not possess stretch, engages with the pulley 19 and 15, this strap being of the endless type, and having graduated or otherwise marked delineated on the outer face angles which the strap subtends at the center of the large pulley 15.

So that these markings on the strap 20 will be readily discernible, I provide a reflector in the form of a mirror or like device 21, which will be located adjacent to the strap, and disposed in such a manner that it may be readily observed, and by looking into this mirror or reflector member, the graduations on the strap directly opposite the mirror will be readily seen, so that the operator will at all times know exactly the angular displacement of the board 16.

Superimposed on the board 16 is a T-square 22, the transverse arms 23 of which embrace the outer face of the lateral guides 12, and the upper face of the T-square 22 is graduated preferably in inches.

As the guides 12 are graduated on the upper face, then by moving the T-square 22, the distance between parallel lines can be readily gaged, and since the T-square is graduated lines of predetermined length can also be drawn, so that scales and protractors are not necessary when using a board of this description.

When the board is in use, the paper, linen or other material on which the drawing is to be done is pinned on the board 16, and as the drawing progresses the board may be rotated about the stub-spindle or pin 14 in a horizontal plane and through any desired angle, the rotation of the board being readily observed, as the angle displacement of the strap is reflected in the mirror.

This board is of an extremely simple construction and there are no parts liable to get out of repair.

As many changes could be made in the above construction, and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

A drawing board comprising a table having end guide members, a drawing board, a pulley attached to the drawing board, a pin carried by the pulley, a bearing centrally

located in the top of the table and designed to receive the pin, anti-friction rollers between the pulley and the table, a second pulley, an endless strap engaging the two pulleys and provided on the outer face with 5 graduations, and a reflector on the table adjacent to the outer face of the strap where-

by the graduated portion of the strap in front of the reflector will be reflected to show the angle of rotation of the drawing board, as and for the purpose specified.

In witness whereof I have hereunto set my hand.

GEORGE HAGAR GILCHRIST.
